UNITED STATES PATENT OFFICE.

JULIAN H. RIVERS, OF ST. LOUIS, MISSOURI, ASSIGNOR TO UNITED STATES FIBRE STOPPER COMPANY, OF ST. LOUIS, MISSOURI, A CORPORATION OF SOUTH DAKOTA.

CLOSURE FOR RECEPTACLES.

SPECIFICATION forming part of Letters Patent No. 737,147, dated August 25, 1903.

Application filed April 27, 1903. Serial No. 154,459. (No model.)

To all whom it may concern:

Be it known that I, JULIAN H. RIVERS, a citizen of the United States, residing at St. Louis, Missouri, have invented a certain new and useful Improvement in Closures for Receptacles, of which the following is a full, clear, and exact description, such as will enable others skilled in the art to which it appertains to make and use the same, reference being had to the accompanying drawings, forming part of this specification, in which—

Figure 1 is a vertical sectional view of the mouth of the bottle, showing a well-known form of cork disk resting thereon. Fig. 2 is a similar view showing the clamping-cap cooperating with the cork disk and illustrating by dotted lines the area of surface-contact between the cork disk and the bottle-mouth. Fig. 3 is a similar view showing my improved plano-convex disk resting on the mouth of the bottle; and Fig. 4 is a view illustrating the metal cap coöperating with the plano-convex disk, the dotted lines showing the extended area of surface-contact.

This invention relates to a new and useful improvement in closures for receptacles and particularly for bottles, the same being designed particularly as an improvement upon what is commonly known as the "Crown stopper," which is a metallic cap-piece having its marginal edges crimped under an exterior shoulder at the mouth of the bottle, the said cap-piece clamping in position a flat thin disk, usually of cork, against the mouth of the bottle. Where cork is used, the pores form communicating openings with the exterior, and a backing of paraffin paper is commonly employed between the cork disk and the metal of the cap. Cork is further objectionable because the tannic acid remaining therein is discolored, forming black specks, which give the impression to many persons of uncleanness. It is because of these objections that the above-mentioned stoppers with the cork disk are used only for domestic purposes, where beer and other liquids are to be locally consumed within a short time. Experiment has demonstrated that for export purposes the stoppers above described are insecure and not satisfactory. Manufacturers, therefore,

rely on the long corks inserted in the neck of the bottle, said corks being at least one and one-half inches long and secured in position by wires or other fastening devices. Such corks for export purposes must be of the better grade and on account of their size are quite expensive.

My present invention consists in a disk to be used preferably in connection with a metallic cap-piece of the "Crown" or other similar stopper. This disk is made of homogeneous paper pulp which is pressed into shape, so that the fibers on the surface are calendered to form a matted or felted integument. These intertwining fibers at the surface preserve the shape of the disk and prevent swelling and disintegration when in contact with liquids. The disk is further made plano-convex in shape, so that its thickened central portion will extend a little distance into the mouth of the bottle. The purpose of this is to increase the area of surface-contact at the mouth of the bottle. Furthermore, to prevent the disk from absorbing the liquid contents of the bottle I prefer to immerse the disk in hot paraffin or other equivalent substance for well-understood reasons.

Referring now to the drawings, 1 indicates the mouth portion of a bottle, having the usual exterior shoulder 2 for coöperating with the crimped margins of the metallic cap-piece 3. These parts are of well-known construction, and I deem it unnecessary to describe the details further or to explain the manner in which the cap-piece is clamped in position, as this is well understood.

4 indicates the thin flat cork disk which is in common use, and I have illustrated this cork disk for comparative purposes. Referring to Fig. 2, it will be seen that the surface-contact between the margins of the cork disk and the mouth of the bottle is comparatively small.

5 indicates the plano-convex pulp disk, whose surface is calendered, as and for the purposes described, said disk being preferably treated with paraffin or other substance to prevent absorption of the liquid contents of the bottle. When this plano-convex disk is placed in position upon the mouth of the bottle

- with the convex side downwardly, the thickened central portion extends slightly into the bottle, so as to increase the surface-contact therebetween and the inner surface of the 5 mouth of the bottle. When the metal cap is used to clamp the disk in place, the margins of the disk are forced over and down onto the outer surfaces of the mouth of the bottle, the material of which the disk is composed readily 10 lending itself to such treatment, and in this way the surface-contact is measurably increased—in fact, to such an extent that bottles closed as above described may with safety be used for export purposes. Furthermore, by the use of 15 my invention paraffin paper, heretofore employed with cork disks, is dispensed with. The disk in color is a grayish white and, containing no acids, which will discolor, it retains a cleanly appearance at all times.
- 20 Having thus described my invention, what I claim as new, and desire to secure by Letters Patent, is—
1. As a new article of manufacture for use as a closure for receptacles, a plano-convex 25 disk made of homogeneously-felted pulp; substantially as described.
  2. As a new article of manufacture for use as a closure for receptacles, a plano-convex disk made of homogeneously-felted pulp and 30 having its surface calendered to form a pro-
- tecting matted integument; substantially as described.
3. As a new article of manufacture for use as a closure for receptacles, a plano-convex homogeneously-felted pulp disk whose surface is calendered to form a protecting matted integument, said disk being treated with a substance to prevent the absorption by the disk of the liquid contents of the bottle; substantially as described. 35
4. The combination with a bottle having a shoulder near its mouth, of a metal cap co-operating with said shoulder, and a plano-convex pulp disk clamped against the mouth of the bottle by the metal cap; substantially 40 as described.
5. The combination with a bottle having an exterior shoulder near its mouth, of a metal cap whose marginal flanges are crimped under said shoulder, and a plano-convex pulp disk 45 fitting in close contact with the inner, upper and outer surfaces of the bottle-mouth; substantially as described. 50
- In testimony whereof I hereunto affix my signature, in the presence of two witnesses, this 16th day of April, 1903.
- JULIAN H. RIVERS.
